UNITED STATES PATENT OFFICE.

HERBERT H. HENNEGGIN, OF ST. LOUIS, MISSOURI.

SAND-BOX FOR CARS.

SPECIFICATION forming part of Letters Patent No. 473,070, dated April 19, 1892.

Application filed January 6, 1892. Serial No. 417,191. (No model.)

To all whom it may concern:

Be it known that I, HERBERT H. HENNEGGIN, of the city of St. Louis and State of Missouri, have invented certain new and useful Improvements in Sand-Boxes for Cars, of which the following is a full, clear, and exact description, reference being had to the accompanying drawings, forming a part hereof.

My invention relates to improvements in "sand-boxes for cars;" and it consists in the novel arrangement and combination of parts, as will be more fully hereinafter described, and designated in the claims.

In the drawings, Figure 1 is a vertical longitudinal section of a railway-car with parts broken away and having my invention applied thereto. Fig. 2 is a vertical longitudinal section of my invention having the various parts attached to the same. Fig. 3 is a top plan view of the gearing which I employ in carrying out my invention, partially broken away. Fig. 4 is a perspective view of the bearing which is secured to the inner surface or floor of the car. Fig. 5 is a cross-section taken on the line $\alpha\alpha$ of Fig. 3, showing the construction of the shaft upon which one of the double gear-wheels are mounted and the means for operating said gear; and Fig. 6 is a front elevation of the separable gear-wheel which I employ and which is carried by the shaft upon which the drive-wheels of the car are mounted.

My invention has for its object to provide the ordinary street-railway car with a sanding device for supplying sand to the rails upon which the car moves in front of the wheels of the same. It is preferably located under the platform of the car, and is operated by a hand-lever or other mechanical contrivance and in easy reach of the operator. The sanding devices heretofore employed for this purpose are such that they will not always feed the sand to the track when it is necessary; but, on the contrary, the said sand will choke in the chute which supplies the said sand to the track, and consequently another contrivance must necessarily be employed to release the sand so choked in the chute. My invention is especially constructed to overcome this objection by employing the arrangement and construction of parts as I

shall now proceed to describe. In practice I employ two of the devices, as hereinafter described, one on each side of the car; but as they are similarly constructed and operated 55 in a like manner I shall only proceed to describe one of them in detail.

Referring to the drawings, 1 represents the car-body, 2 the platform of the same, and 3 the shaft of one of the sets of wheels upon 60 which the said car-body is mounted in the usual manner. To said shaft 3 is rigidly secured a gear-wheel 4, which is united to said shaft and is detachable therefrom, as I shall now proceed to describe. Said gear-wheel 4 65 is divided into two parts 5 and 6, the said parts being hinged together by means of a hinged joint 7 and the opposite ends of said parts united by means of a bolt 8, passing through suitable holes formed in the ears 9 70 of said sections. By the employment of the construction as above described the said gear-wheel can be easily placed on the shaft 3 and removed from the same without in any way disconnecting any of the parts of the ordinary car.

10 represents a bearing, which is secured to the under surface of the floor of the car adjacent to the platform of the same, the lower end of said bearing depending and 80 adapted to support a rotating shaft 11, which shaft is comparatively short and upon the ends of which are mounted and keyed to the same bevel gear-wheel 12 and gear-wheel 13, as best shown in Fig. 3.

85 14 represents a chain, which passes over the gear-wheel 4 and also over the gear-wheel 13, forming a connection between the shaft 3 of the car and the short shaft 11. By the above construction the bevel gear-wheel 12 will under all circumstances revolve or rotate when motion is imparted to the axle or shaft 3 of the car, but said bevel gear-wheel 12 will not impart motion to the sanding device until the mechanism is operated, as hereinafter more 90 95 specifically referred to.

15 represents a box or receptacle having converging sides and having its upper edge secured in any manner to the under surface of the bottom of the platform 2 of the car, promising, however, that a suitable opening is 100 formed in the platform, and a door, such as 16,

corresponding in size to said opening, is adapted to cover the top of said box or receptacle. Within said box or receptacle 15 is placed the sand to be supplied to the track-rail. The bottom 17 of said box or receptacle has an opening 18, which opening communicates with a trough 19 of suitable length, and formed in the bottom of the said trough, near the end of the same, is an opening 20, 10 which communicates with the chute 21 or exit for the sand.

22 represents a shaft, which is mounted within the trough 19, and secured to said shaft or to that portion located within said 15 trough is a conveyer 23, which when rotated in the proper direction will cause the sand to be fed from the box or receptacle 15 to the chute 21. Should there be any lumps in the sand contained in the box 15, the conveyer 20 above described will break the same, and at the same time convey the sand, as above described. The projecting end of the shaft 22 is provided with a feather 24, which allows the bevel gear-wheel 25 to be moved in a longitudinal 25 direction and at the same time lock the said gear-wheel against rotation independent of said shaft. Said beveled gear-wheel 25 when in the position as shown in Fig. 2 of the drawings will not be rotated by the mechanism, as previously described; but when said gear-wheel is moved to the right, referring to the said drawings and better illustrated in Fig. 2, the shaft 22 will be rotated, the said bevel-gear being brought in connection with the beveled gear-wheel 12, carried 30 upon one end of the shaft 11.

The beveled gear-wheel 25 is provided with a flanged extension 26, forming a neck 27, around which the forked end of the rod 28 is 40 placed.

29 represents an operating-lever, which is fulcrumed in the platform 2 of the car, and to the short arm of said lever is loosely attached the opposite end of the rod 28, or, rather, 45 that end of said rod opposite to the forked end on the same. 30 represents the forked end of the said rod, as better illustrated in Fig. 5, by which construction the lever 29, when pulled to the right, referring to Fig. 1, the bevel gear-wheel 25 will be released from contact with bevel-wheel 12, and consequently no motion will be imparted to the conveyer 23. However, when it is desired to throw the 50 gearing in contact with one another the lever 29 is pushed in the opposite direction, as shown in Fig. 1, and motion imparted to the conveyer 23. As the sand is only conveyed to the track under certain circumstances and when it becomes necessary, I find it practicable 55 to employ certain mechanism, as hereinafter described, to normally press upon the bevel gear-wheel 25 and prevent the said gear-wheel from being rotated only when it is necessary.

31 represents a collar, which is secured to 60 the extreme end of the shaft 22, and inter-

posed between said collar and the bevel gear-wheel 25 is a coil-spring 32, which accomplishes the object as desired.

It will be readily understood that when it is desired to convey sand to the track the coil-spring 32 will be compressed so long as the lever 29 is pushed in the direction as shown in Fig. 1.

I do not wish to limit myself to the precise construction as above described, as the same 75 may be changed or modified without departing from the true nature of my invention.

Having fully described my invention, what I claim is—

1. A sand - box for cars, consisting of a 80 trough, such as 19, in communication with said box, a conveyer, such as 23, located within the said trough and in contact with the sand contained in said box, a gear-wheel mounted upon the axle of the car, suitable 85 gearing between said gear-wheel and conveyer for imparting motion to the same, and means for disconnecting said gearing, substantially as set forth.

2. A sand - box for cars, consisting of a 90 trough, such as 19, attached to the lower surface or bottom of said box and in communication with the same, a shaft, such as 22, mounted within the said trough, a conveyer 95 23, secured upon the shaft 22, for conveying the sand to the track, a bevel gear-wheel 25, loosely mounted upon the said shaft and adapted to move in a longitudinal direction, a gear-wheel, such as 4, mounted upon the axle of the car, a bearing, such as 10, secured to the under surface of the car, a shaft, such as 11, mounted in said bearing and carrying gear-wheel 13 and bevel gear-wheel 12, a chain, such as 14, forming a connection between said gear-wheels 4 and 13, and means 100 for throwing the bevel gear-wheels 25 and 12 in and out of gear, substantially as set forth.

3. A sand - box for cars, consisting of a trough, such as 19, attached to the lower surface or bottom of the said box and in communication with the same, a shaft, such as 22, mounted within said trough, a conveyer 110 23, mounted upon said shaft, a bevel gear-wheel 25, loosely mounted upon said shaft and adapted to be moved in a longitudinal 115 direction, a flanged extension 26, formed with the said gear-wheel 25, a lever, such as 29, fulcrumed in the bottom of the platform of the car, a rod, such as 28, connected to the said lever, a fork, such as 30, formed on the opposite end of the said rod, spanning the neck 27 of said extension, and means for imparting motion from the axle of the car to said conveyer, substantially as set forth.

In testimony whereof I affix my signature in 125 presence of two witnesses.

HERBERT H. HENNEGIN.
